R. R. ARMOR.

GAS BURNER.

APPLICATION FILED APR. 5, 1915.

1,174,650.

Patented Mar. 7, 1916.

Robert R. Armor

Inventor.

By Wm. N. Moore

Attorney.

UNITED STATES PATENT OFFICE.

ROBERT R. ARMOR, OF LOS ANGELES, CALIFORNIA.

GAS-BURNER.

1,174,650.

Specification of Letters Patent.

Patented Mar. 7, 1916.

Application filed April 5, 1915. Serial No. 19,197.

To all whom it may concern:

Be it known that I, ROBERT R. ARMOR, a citizen of the United States, residing at Los Angeles, in the county of Los Angeles and State of California, have invented certain new and useful Improvements in Gas-Burners, of which the following is a specification.

My invention relates to improvements in 10 gas heaters or burners, and refers particularly to burners for use with natural gas.

One object of my invention is the provision of a burner to be used for heating purposes in the home, in fire places, sheet iron 15 stoves and in fact in any place where it would operate properly.

Another object of my invention is the provision of a burner in which the mixture of air with the gas is perfect, insuring better 20 combustion than obtained with the burners now in use.

Another object of my invention is the provision of a gas burner of the character stated which can be produced at a low cost, 25 which will insure the most efficient results and which will be practical in every particular.

With these objects in view my invention consists of a gas burner embodying novel 30 features of construction and combination of parts substantially as shown, described and particularly defined by the claim.

Figure 1 represents a side elevation of 35 a gas burner, constructed in accordance with and embodying my invention. Fig. 2 represents a central sectional view of my invention. Fig. 3 represents a detail view of the gas distributor, and Fig. 4 is a view showing the mixing chamber.

40 In the drawings: the letter A designates the gas feed or supply elbow, having the threaded end B, for attachment to the gas supply pipe and the threaded end C which engages the threaded end D of the gas distributor E. The distributor E has the hexagon shaped flange portion F for screwing it in the elbow A, and on its other end the distributing cap or head G, having the series of discharge openings H and the circular closed wall J. The said wall J, of 45 the distributor E fits the opening K, of the cross arm L, of the cone-shaped mixing chamber M, said mixing chamber having the air inlet opening M', the globular portion N, and the threaded portion O. It will

thus be understood that the gas passes through the elbow A, into distributor E, and by way of the distributing openings H, into the mixing chamber M, thereby causing a thorough mixing of the gas with the air 60 which is admitted through opening M', by reason of the globular portion N, which causes the gas and air to have an eddying movement thereby mixing the gas and air more thoroughly.

Engaging the thread receiving portion O of the mixing chamber M, is the threaded end P, of the coupling Q, said coupling having a globular or enlarged portion R, which causes the gas and air to keep up the 65 eddying movement and also the coupling has the threaded receiving portion S. Engaging the threaded receiving portion S, is the threaded end T of the pipe nipple U, having the threaded end T' engaging the 70 thread receiving portion V of the burner head V', having the holes or openings W to allow the exit of the gas for ignition. 75

It will be apparent that the gas is fed to the elbow and thence to the distributor 80 which by reason of the series of openings thoroughly divides the gas into a series of jets or streams. The streams are supplied to the conical mixing chamber with air and in this state the gas is again thoroughly 85 mixed after leaving the mixing chamber and supplied in perfect condition to the burner head insuring the highest efficiency for the purposes intended.

From the foregoing description it will be 90 apparent that I furnish a burner that will be simple, durable and desirable from every point of view; one that will be inexpensive to make and economical in consumption of gas; and one that will be compact and neat 95 of appearance, and which will be of use in any place where a gas burner is desired.

I claim:

The combination in a gas burner with a 100 cone shaped mixing chamber and a supply pipe having a distributor projecting in said chamber, of air inlets to said chamber, a cross-arm formed with an opening to receive said distributor, a globular chamber integral with and communicating with said cone shaped chamber, whereby the currents of air and gas are commingled by the eddying movement given the currents of air and gas by said globular chamber, a burner 105 head, a pipe leading thereto, and a coupling 110

connecting said pipe and mixing chamber,
said coupling having a second globular
chamber in communication with the first
concave chamber, whereby the eddying
movement of the air and gas is continued
5 causing a further commingling of the air
and gas.

In testimony whereof I affix my signature
in presence of two witnesses.

ROBERT R. ARMOR.

Witnesses:

J. L. THOMSON,
J. SPELLACY.
